ANTISKID DEVICE

William H. Snyder, Elkins Park, Pa.

Application June 22, 1938, Serial No. 215,156

1 Claim. (Cl. 152—220)

My invention relates to a new and useful anti-skid device and it relates more particularly to an antiskid device especially adapted for use in connection with dual tires on trucks and the like.

5 My invention still further relates to an anti-skid device which is not only efficient in gripping the road surface but one which is also effectively retained in place and at the same time easy to apply or remove.

10 The construction and advantages of my novel device will be more clearly understood from the following specification and the accompanying drawings in which:

Fig. 1 represents a side elevation of a dual wheel assembly, one-half of the wheel being shown.

15 Fig. 2 represents a plan view of a dual wheel assembly provided with an antiskid device embodying my invention.

Fig. 3 represents a section on line 3—3 of Fig. 2. 20 Fig. 4 represents a plan view of the road-engaging cross bar forming part of my invention and illustrating certain details of construction.

Fig. 5 represents a fragmentary plan view illustrating the manner in which the supporting chain is secured to the cross bar shown in Fig. 4.

25 Fig. 6 represents a section on line 6—6 of Fig. 5.

Fig. 7 represents a section on line 7—7 of Fig. 5.

30 Fig. 8 is a fragmentary view showing the manner in which the ends of the two adjacent cross bars, such as that shown in Fig. 4, are interconnected.

Fig. 9 represents a fragmentary view showing the manner in which the ends of the chain are 35 clamped together.

Referring to the drawings in which like reference characters indicate like parts and more particularly to Fig. 2, 10 and 12 designate dual wheels carried by the hub 14. 16 designates a 40 cross bar having notched edges 18 and adapted to be disposed angularly of the tread of the tires 10 and 12, it being understood that a suitable number of bars 16 is used so that the adjacent ends of two converging bars are approximately 45 disposed as shown in Fig. 2. This arrangement permits the use of the least number of bars 16 and at the same time affords continuous traction, since, as the bar 16 to the right of Fig. 2 is gradually disengaged from traction with the 50 road, the adjacent end of the bar 16 to the left of Fig. 2 begins to engage the road. The ends 20 of the bars 16 are provided with the apertures 22 which are engaged by the relatively heavy links 24 and also with the holes 26, which, by 55 means of the links 28 are engaged to the sup-

porting chain 30. An interconnecting link 32 connects the chain links 24 to the supporting chain 30. The ends of the supporting chain 30 are drawn tight and secured together by the clamp 34 which engages one end of the chain at 5 36, with the other end of the chain engaged in its open jaw 38. The hooked end 40 of the clamp 34 is then swung in the direction of the arrow in Fig. 9 so that the hook 40 engages the chain 30 and thus effects a tight connection. It is understood that two chains 30 are used, one on the 10 inboard side of the inner tire, and one on the outboard side of the outer tire of the dual assembly, and in order to keep the bars 16 in position and further to support the same I utilize the 15 auxiliary chain 42 the ends of which are connected together by a clamp 34 in the same manner as the chains 30. Carried by the upper side of the bar 16 is the boss 44 which is notched or cut away to form the opening 46 with the jaws 20 48 on either side thereof. The boss 44 is also provided with a transverse recess 50 which intersects the vertical recess 46 as best seen in Fig. 3. In order to secure the bar 16 to the chain 42 the link 52 of the chain 42 is introduced in a vertical manner into the vertical opening 46. The link 52 is then moved through an angle somewhat greater than 150° so that only the bottom edge of it is still in the slot 46 and the rest of the link is in an out-of-the-way position with respect 25 to the horizontal slot 50 to render the latter accessible. The locking plate 54 is then inserted into the horizontal slots 50 in the direction of the arrow in Fig. 4. With the plate 54 in the slot 50 the link 52 cannot be removed from the slot 30 46 as best seen in Fig. 6. Since normally the 35 position of the link 52 is vertical, and that of the links 56 and 58 is horizontal, it will be seen that once the locking plate 54 is introduced into the slot 50 while the link 52 is in a horizontal 40 position, the plate 54 is sufficiently locked against displacement. However, in order to guard positively against disengagement of the locking plate 54, if the link 52 should accidentally be turned about its longitudinal axis to assume a position 45 in which it will not obstruct the recess 50, I have provided the cotter pin 60 which passes through the jaws 48 on either side of the slot 46 and which serves to prevent the link 52 from being deflected enough to permit the plate 54 from coming out 50 of the slot 50. It will be understood that each of the bars 16 is provided with the boss 44 on its inner or upper surface, and that at each point at which the bar 16 crosses the auxiliary chain 42 the bar 16 is secured to the chain 42 in the man- 55

ner just described and clearly illustrated in Figs. 3, 5, 6 and 7.

Having thus described my invention, what I claim as new and desire to secure by Letters Patent is:

An antiskid device for a dual tire assembly comprising road-engaging bars straddling the treads of dual wheels and disposed at an angle to the direction of rotation of said wheels, end 10 chains engaging the opposite ends of said bars to fasten the same to said dual wheels, a central chain disposed between said dual wheels and means for detachably securing said chain to the

adjacent portions of said bars comprising a boss projecting from the inner surface of each of said bars and having a vertical slot formed therein adapted to receive a link of said central chain, a horizontal slot formed in said boss and intersecting said vertical slot, a locking plate adapted to be inserted in said horizontal slot through a link of said central chain which is seated in said vertical slot detachably to lock said link in said slot, and means for preventing accidental disengagement of said locking plate from said horizontal slot. 5 10

WILLIAM H. SNYDER.
